UNITED STATES PATENT OFFICE.

JOSEF ENGL AND JOSEPH MASSOLLE, OF BERLIN-GRUNEWALD, AND HANS VOGT, OF BERLIN-WILMERSDORF, GERMANY, ASSIGNORS TO TRI-ERGON, LIMITED, OF ZURICH, SWITZERLAND, A CORPORATION OF SWITZERLAND.

ACOUSTIC-CINEMATOGRAPHIC APPARATUS.

Original application filed April 4, 1921, Serial No. 458,629. Divided and this application filed October 29, 1924. Serial No. 746,741.

To all whom it may concern:

Be it known that we, JOSEF ENGL, JOSEPH MASSOLLE, and HANS VOGT, citizens of the German Republic, residing, respectively, at

5 Berlin-Grunewald, Berlin-Grunewald, and Berlin-Wilmersdorf, Germany, have invented certain new and useful Improvements in Acoustic Cinematographic Apparatus, of which the following is a specification.

10 The invention relates to improvements in acoustic-cinematographic apparatus, that is to say apparatus in which moving pictures are made and sounds accompanying the pictures are simultaneously recorded, the pictures 15 and sound records being, for example, recorded upon the same film; the pictures and sounds subsequently being synchronously reproduced by means involving the passage of light thru the positive film made 20 from the negative thus produced.

An object of the present invention is the improvement of the quality and volume of the sound recorded and subsequently reproduced by means involving the use of amplifiers in 25 such a way as to prevent certain electrical disturbances and consequent distortion of the sound-modulated current and the sound itself as finally reproduced. The present application is a division of our application, 30 Serial No. 458,629, filed April 4, 1921 and entitled improvements in arrangement for acoustic-cinematography.

In making the sound record on the negative film, the sound affects a microphone 35 whereby a corresponding sound-modulated current is set up which current affects a recording light, the variation of which makes a photographic record upon the negative film, the variations of which should correspond to the sound which is to be recorded. 40 In reproducing, light from a suitable source is caused to pass thru the moving positive film, which has been made from the negative film, thus produced, and this light falls 45 upon a suitable light-sensitive device, such as a photo-electric cell.

The variations in the photo-electric cell caused by the action of the light thereupon, 50 set up acoustically-modulated currents, that is current varying in correspondence with the sound to be reproduced, and these cur-

rents actuate a form of telephone or loud speaker whereby the sound is reproduced. The above generally described form of apparatus is, of course, well known.

These known arrangements have, however, important disadvantages. The acoustically-modulated currents in both receiving and reproducing are very small being, for example, of the order of magnitude 10^{-6} to 10^{-4} amperes, the result of which is that the sound produced, without amplification, will be too weak for suitable reproduction in a large hall or the like. Furthermore, the use of amplifiers in such systems present various difficulties. The employment of low-frequency amplifiers has the disadvantage that, in accordance with prior practice, low frequency transformers have to be used as coupling means. Such use causes a falsification of the sound reproduced and of the tone color of the same and also amplifies all disturbing noises. This is for the reason that strong electromagnetic disturbances are caused in moving picture work by various factors, the effect of which is especially marked on the amplifier circuit of the acoustic system if the use of amplifiers in the latter is attempted. These effects are produced for example, by the projection arc lamp used for 80 making pictures and the projection machine motor in the reproducing system (both closely adjacent to the acoustic operations), the lamp by which the stage is lighted for the recording system, etc. If low-frequency 85 transformers are used in the connections in the acoustic system, distortion of the acoustically-modulated currents is produced, because of magnetic hysteresis effects, undesired resonance and disturbing low-frequency alternating fields, affecting the transformers, as the result of causes, such as those mentioned.

In consequence of the above, such methods of amplification have hitherto not obtained 90 importance in practice in acoustic-cinematography. The impression received by the audience, which should be one of synchronism between the optical and the accompanying acoustic operation, may be annulled by distorted reproduction of the speech or other sounds, especially if ampli- 100

fication of such speech or sounds, and accordingly a magnification of the distortion thereof, is necessary.

The present invention aims to provide an arrangement which makes possible amplification of the sound-modulated current, free from distortion and without the above described disadvantages. The invention is carried out by so connecting the elements of the acoustical system, including amplifying means as to overcome the distorting effect thereon of the various disturbing factors, by which they may be influenced.

The arrangement consists in the combination of the recording and reproducing means, (microphone, photocells, etc.) with amplifiers (vacuum tubes) which possess no inertia, and whose elements are galvanically, i. e., resistance-coupled without the use of low frequency transformers. The recording and reproducing means referred to, comprising, with the amplifiers, the elements of the system, include the microphone in the recording system and the photo cell in the reproducing system and also the telephone or loud speaker by which the sound is eventually reproduced in the reproducing system. The invention further consists in the combination and arrangement of parts all as will be more fully stated in the following specification, and particularly pointed out in the appended claims.

The invention may also be carried out by the provision of inertia-free high frequency amplifiers coupled together by high frequency transformers having air cores and consequently free from iron, this arrangement being for use in a system in which high frequency alternating current from a suitable source is employed. Such high frequency transformers are relatively insensitive to disturbances by low frequency fields.

In our said application, Serial No. 458,629, the species of invention involving the use of high frequency transformers referred to is included and in the present application the species of invention involving the use of resistance coupling will be claimed.

In order that the invention may be more clearly understood, attention is hereby directed to the accompanying drawings illustrating diagrammatically by way of example, recording and reproducing systems, in which the invention may be used.

Referring to the drawings, Fig. 1 represents diagrammatically a system for simultaneously recording, on a moving film, pictures and the accompanying sounds; Fig. 2 represents diagrammatically a system for reproducing, from a moving film, pictures and the accompanying sounds.

In Fig. 1 a pair of thermionic amplifiers are indicated as resistance-coupled in a system for recording sound on a moving film. The film is indicated diagrammatically at 1,

the moving pictures being produced on the film by the usual means indicated diagrammatically by the projecting lenses 2 of the moving picture apparatus 3, pictures thus being made for example of actors upon a stage 4 illuminated in the usual way by electric lamps, which are indicated at 5-5.

The speech or other sounds produced by the actors or accompanying their action fall upon a microphone indicated diagrammatically at 6. A current is accordingly produced in the circuit 7, leading from the microphone, which current is sound-modulated, that is it fluctuates in correspondence with the sound producing the same. This circuit leads to a thermionic amplifier 8, one side of the circuit being connected to the usual filament 9 of the amplifier and the other side to the grid 10, in the usual manner.

Amplified current flows from the plate 11 of amplifier 8 to the grid 10¹ of a second amplifier 8¹, it being understood that as many amplifiers are used in this system as is found desirable. From the last amplifier of the series, illustrated as the amplifier 8¹, an output circuit 12 is indicated as leading to a recording lamp indicated diagrammatically at 13. The illumination of this lamp is varied in accordance with the sound modulated current received thereby and the light thus varied falls upon the film 1 to make a negative record corresponding to the sound as is well known. The amplifiers of the system are coupled together by resistances, resistance 15 being indicated as connected across the output circuit of amplifier 8 in the well known manner. Similarly the microphone 6 is illustrated as resistance coupled to the first amplifier 8, resistance 15^a being shown as connected across the circuit leading from the microphone to the filament and grid of the tube 8. Batteries, 16, 16^a and 16^b are conventionally indicated as included in the circuits 7, 17 between the amplifiers, and 12 extending between amplifier 8¹ and the recording lamp 13, this being, of course, common practice. A resistance 15^b is also indicated as included in the circuit 12 leading from the last amplifier. Condensers 18 and 18^a are indicated in the grid leads of amplifiers 8 and 8¹, merely by way of example. It may be noted that coupling resistance 15^a for the microphone corresponds to the resistance described in our copending application Serial No. 458,632, entitled Method for the control of electric currents by power of sounds, filed April 4, 1921, and there stated to be the coupling resistance of the microphone for amplifying or intensifying tubes.

Fig. 2 represents by way of example, the manner in which the invention may be used in the reproducing system. As there shown, the positive film 1^a bears the positive sound and picture records. The pictures are pro-

jected by a suitable light source, such as the arc lamp indicated diagrammatically at 19, the light from the same being indicated conventionally as passing thru a lens 20, thus thru the filament and then by lens 21 upon the screen 22. In the accompanying acoustical system, light from a suitable source 23 is projected through the sound record on film 1^a and falls upon photo-electric cell 24. The cell 24 is connected by a circuit 25 with a suitable amplifying tube 26. The two sides of the circuit are indicated conventionally as extending to the grid and filament of tube 26, a resistance coupling 27 being indicated as connected across the grid and filament leads of tube 26. The output circuit of tube 26 is connected to the next amplifier 28 of the series, a resistance coupling 29 being indicated as connected across the grid and filament leads of the second amplifier. The plate and filament of the last tube are indicated as connected by circuit 32 to the telephone indicated diagrammatically at 30 by which the sound is reproduced, and resistance 31 being indicated as connected around the telephone. Sound modulated current is produced by the photo electric cell 24 and this is amplified by the amplifiers without distortion and eventually causes reproduction of sound by the telephone or loud speaker 30.

We claim:

- 35 1. In acoustic-cinematographic apparatus, including an electric device, adapted to cause electro-magnetic disturbances in adjacent electrical apparatus, the combination of means for producing an acoustically modulated electric current, a plurality of thermionic amplifiers, and connections between all of said elements including resistance couplings between adjacent amplifiers, adapted to avoid the disturbing effect of said electric device on the circuits of said amplifiers.
- 40 2. In acoustic-cinematographic apparatus, including an electric device adapted to cause electro-magnetic disturbances in adjacent electrical apparatus, the combination of elements of an acoustic system, comprising means for producing an acoustically-modulated electric current and a plurality of thermionic amplifiers, and connections comprising resistance couplings between all of said

elements, adapted to avoid the disturbing effect of said electrical device on the circuits of said amplifiers.

55

3. In acoustic-cinematographic apparatus, including a light source of a moving picture apparatus, adapted to cause electro-magnetic disturbances in adjacent electrical apparatus, the combination of elements of an acoustic system, comprising means for producing an acoustically-modulated electric current and a plurality of thermionic amplifiers and connections comprising resistance couplings between various of said elements, adapted to 60 avoid the disturbing effect of said light source on the circuits of said amplifiers.

4. In acoustic-cinematographic apparatus, including an electric device adapted to cause electro-magnetic disturbances in adjacent 70 electrical apparatus, the combination of means for producing an acoustically-modulated electric current, a thermionic amplifier, and a resistance coupling for connecting said first named means to said amplifier, to avoid 75 the disturbing effect of said electrical device on the circuits of said amplifier.

5. In acoustic-cinematographic apparatus including an electric device adapted to cause electro-magnetic disturbances in adjacent 80 electrical apparatus, the combination of a microphone, a thermionic amplifier, and a resistance coupling for connecting said microphone to said amplifier, to avoid the disturbing effect of said electrical device on the 85 circuit of said amplifier.

6. In acoustic-cinematographic apparatus, the combination of a moving picture machine having an electric light source, capable of causing electro-magnetic disturbances in 90 adjacent apparatus, acoustic apparatus comprising means for producing an acoustically-modulated electric current, thermionic amplifying means and connections between various of said means comprising resistance 95 couplings, said acoustic apparatus operating simultaneously with said moving picture machine and being close enough thereto to be affected by disturbances produced by said light source.
